(57) **CLAIM**

The ornamental design for a handheld transceiver, as shown and described.

DESCRIPTION

FIG. 1 is a front elevational view of a handheld transceiver showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a front and left side perspective view thereof;
FIG. 8 is a rear and right side perspective view thereof;
FIG. 9 is a bottom, front and right side perspective view thereof;
FIG. 10 is a bottom, rear and right side perspective view thereof;
FIG. 11 is a top, rear and right side perspective view thereof; and,
FIG. 12 is a top, front and left side perspective view thereof. The broken lines and the area where the broken lines occur, within the innermost of the two closely spaced, solid line, concentric circles at the top rear of the antenna, show portions of the handheld transceiver that form no part of the claimed design.
